UNITED STATES PATENT OFFICE.

CHARLES E. FOULKS, OF COVINGTON, KENTUCKY.

STARTING-GATE FOR RACE-TRACKS.

No. 807,161.

Specification of Letters Patent.

Patented Dec. 12, 1905.

Application filed July 3, 1905. Serial No. 268,181.

To all whom it may concern:

Be it known that I, CHARLES E. FOULKS, a citizen of the United States, residing at Covington, in the county of Kenton and State of Kentucky, have invented certain new and useful Improvements in Starting-Gates for Race-Tracks; and I do hereby declare the following to be a full, clear, and exact description of the invention, such as will enable others skilled in the art to which it appertains to make and use the same.

My invention relates to starters for race-tracks. One of its objects is to provide improved means for elevating the tape and arms when released.

Another object is to provide improved latch and trigger mechanism.

Another object is to provide improved and positive means for simultaneously releasing the arms at opposite sides of the track.

It further consists in certain details of form, combination, and arrangement, all of which will be more fully set forth in the description of the accompanying drawings, in which—

Figure 1 is a perspective view of my improved device in position for use. Fig. 2 is a detail view of one of the arms in the raised position. Fig. 3 is a sectional detail of one latch and trigger. Fig. 4 is a similar view of the opposite latch. Fig. 5 is a top plan view of Fig. 4. Fig. 6 is a detail sectional view of the cam-brake mechanism. Fig. 7 is a horizontal section through the post, showing a modified attachment for the supporting-frames. Fig. 8 is a front elevation of the same.

A A' represent posts permanently located at opposite sides of the track.

B B' represent supporting-frames detachably mounted upon the posts by means of the loops or staples α and bars α' entering slots β' at the lower ends of the frames or, preferably, as shown in Figs. 7 and 8, by means of cross-bars 2, pivoted to brackets 3, secured to the posts A A'. The bars 2 are provided with set-screws 4, the ends of which bear against lugs 5 of the brackets and serve to turn the frames B B' so that the arms D D' will travel in parallel lines. The bars α' may be likewise but not as conveniently adjusted by means of washers or spacing-blocks 7 between the bars α' and the posts.

At the upper ends of the frames are horizontal studs C C', upon which are journaled arms D D'. The shanks d d' of the arms exert a spring tension on the tape E to hold the same taut, which is preferably effected by

forming loops d^2 in said shanks. At the opposite ends arms D D' are provided with curved or cam-shaped projections F F', having grooved faces f f' to receive the cords g g' , which are attached to the arms near the journals of the arms and their free ends connected to the springs G G', which in turn are connected at their opposite ends to cords g^2 g^3 , passing over the ends of the brace-bars H H'. 65

I I' represent latches mounted in frame-pieces s s' and projecting up so as to close the mouth of recesses j j' in the upper faces of the pieces s s' . The latches are held in place by means of springs O and locked by triggers J J', which engage pins S S' on the latches I I'.

L represents a cord passing across the track, being preferably supported upon pulleys S². One end terminates in a ring or loop m, which is drawn down and engages over a pin M, 75 which projects from the arm d and which pin is withdrawn from the ring when the latch is tripped and the arm D released. At the opposite end the cord L is attached to a spring-actuated lever N, which it holds in the raised 80 or horizontal position as long as pin M and ring m are in engagement, but is thrown downward by its spring as soon as the ring is released. A pin n on the trigger J' enters a segmental slot n' in lever N, thus allowing 85 considerable movement without releasing the trigger J', which is important to prevent the accidental release of the trigger due to vibrations of the cord L. As soon as the ring m has been engaged with pin M the cord is drawn 90 down at the opposite end, the trigger J' adjusted to position, and the end of the cord drawn into the coils of spring n² on the end of lever N, where it is tightly held, and lever N is free to move a limited distance without releasing trigger J'. When ring m is released, the lever N pulls the cord through the pulleys and releases the trigger J', a stop n³ preventing the cord being drawn too far. Thus the latch-bar I and arm D' are released almost 100 simultaneously with the release of arm D.

In practice the arms are simultaneously brought down and latched by separate attendants and the cord and its adjuncts adjusted to position. It will be noted that the 105 curved projections regulate the tension of the springs on the arms, so that the tension is greatest when the shanks are down and gradually decreases as they rise. The sleeves or journals d⁴ have cam-faces at d⁵, which engage corresponding cam-faces on the collars d⁶ when the shanks d d' have nearly reached 110

a vertical position above the studs C C' and force the sleeves d^4 endwise on the studs against the leather friction-disks R, thereby serving to bring the arms D D' gently to a 5 rest without undue strain, sudden jar, or noise, which would be liable to injure the apparatus or frighten the horses. The spring-arms P P' also serve to engage the cords g g' at the same time and assist in bringing the 10 arms D D' to rest. It will also be noted that the frames and operative parts may be readily detached from one set of posts and removed and quickly set upon other posts at any part of the track, as required.

15 What I claim is—

1. In a starter, the detachable supporting-frames carrying latch and trigger mechanism and horizontal studs, hubs journaled on said studs and provided with spring tape-carrying 20 arms at one side to strain the tape and eccentrically-curved arms at the opposite side, and tension-cords engaging said curved arms to rotate the hubs and lift the tape when the latches are released.

25 2. In a starter, supporting-frames at opposite sides of the track provided with latch mechanism and horizontal studs, tape-carrying arms journaled at an intermediate point on said arms to said studs, the ends of the arms at 30 the opposite side of the journals from the tape being curved and recessed to retain the tension-cords, and tension-cords resting on said curved ends of the arms to rotate the arms and lift the tape when the latch is released.

35 3. In a starter, supporting-frames at opposite sides of the track provided with latch mechanism and horizontal studs, arms journaled on said studs with tape-carrying shanks adapted 40 to engage the latch mechanism, means for turning said arms on their journals to raise the tape when the latch is released, faces adapted to frictionally engage each other to bring the arms to rest, and cam-faces adapted 45 to force said faces into contact when it is desired to bring the arms to rest.

4. In a starter, supporting-frames at opposite sides of the track carrying latch mechanism and studs to receive the tape-carrying 50 arms, arms journaled on said studs carrying a tape and adapted to be engaged by the latch mechanism a cord passing across the track from one latch mechanism to the other, one end of said cord being released by the withdrawal of a pin by the latch mechanism at 55 one side of the track from an eye in the cord, and the opposite latch mechanism being released by the endwise movement of the cord.

5. In a starter in combination with supporting-frames and tape-carrying arms movable relative thereto, latch mechanisms to lock said arms in the lower position consisting of the recessed frame-pieces, beveled latch-bars adapted to automatically permit the passage 60 of the arms in either direction over said latch-

bars, and triggers to engage and lock the latch-bars in position to hold the arms, and to be tripped to release the latch-bars when it is desired to operate the starter.

6. In a starter, a latch mechanism to release 70 the distant tape-arm consisting of a latch-bar, a trigger to lock the latch-bar in position to hold the arm, a spring-actuated lever having a slot, and a pin projecting from the trigger through said slot.

7. In a starter, supporting-frames at opposite sides of the track having latch mechanism and horizontal studs, tape-carrying arms journaled on said studs and adapted to turn through an arc of substantially ninety degrees, said 80 arms having their ends opposite to the tape eccentrically curved and channeled to retain the tension-cords, and tension-cords resting on said curved ends and adapted to rotate said arms when released by the latch.

8. In a starter, detachable supporting-frames located at opposite sides of the track and provided with tape-carrying arms, and latch mechanism, said frames being secured to permanent posts by straps, and prevented 90 from turning by slots in the frames engaging bars attached to the posts.

9. In a starter, supporting-frames at opposite sides of the track provided with latch mechanism and horizontal studs, arms journaled on said studs with tape-carrying shanks at one end adapted to engage the latch mechanism and with curved projections at the opposite ends, tension-cords resting on said curved projections to rotate the arms and lift 100 the tape when the latch is released, and stop-arms adapted to strike and rest on said tension-cords to limit the motion of said arms.

10. In a starter, detachable supporting-frames located at opposite sides of the track 105 and provided with tape-carrying arms and latch mechanism, permanent posts to which said frames are detachably secured, and means for rotatively adjusting said frames relative to the posts to bring the arms into alinement.

11. In a starter, supporting-frames carrying latch and trigger mechanism and horizontal studs, arms journaled on said studs having tape-carrying shanks and means for turning 115 said arms on their journals to raise the tape when the latches are released, a cord leading from one trigger mechanism to the other, and terminating at one end in a ring, a pin to engage the ring when the arm is latched in position, and mechanism to release the ring when 120 the arm is unlatched.

12. In a starter, a near tape-arm to be directly released by the operator, a distant tape-arm to be released simultaneously with the near tape-arm, a latch-bar to engage the distant tape-arm, a trigger to lock said latch-bar in position to hold said distant arm, a spring-actuated lever to release said trigger, a cord passing across the track and adapted to hold 125 said spring-actuated lever out of contact with 130

the trigger until the near tape-arm is released, and means for releasing said cord simultaneously with the release of said near tape-arm.

13. In a starter, permanent posts located at 5 opposite sides of the track and provided with members to engage and prevent the rotation of the detachable supporting-frames, and detachable supporting-frames provided with members adapted to engage and interlock 10 with the members on the permanent posts,

1 said supporting-frames being provided with pivoted tape-carrying arms and latch mechanism therefor.

In testimony whereof I have affixed my signature in presence of two witnesses.
